Fig. 3.

FIG. 1 is a perspective view of a bottle showing my new design;

FIG. 2 is a bottom elevational view thereof; and

FIG. 3 is a side elevational view thereof.

The characteristic features of my design reside in the appearance and configuration of the bottom portion of the bottle located below the vertical side walls.

The application is a continuation-in-part of Ser. No. D. 131,585, filed Apr. 5, 1971.

I claim:

The ornamental design for a bottle, substantially as shown and described.
